HIS ATTORNEY

UNITED STATES PATENT OFFICE.

JULIUS M. BORN, OF ST. PAUL, MINNESOTA.

LUGGAGE CARRIER.

1,418,426.

Specification of Letters Patent. Patented June 6, 1922.

Application filed December 1, 1920. Serial No. 427,527.

To all whom it may concern:

Be it known that I, JULIUS M. BORN, a citizen of the United States, residing at St. Paul, in the county of Ramsey and State of Minnesota, have invented certain new and useful Improvements in Luggage Carriers, of which the following is a specification.

This invention relates to devices for use in connection with that type of luggage carriers, adapted to be secured to the running board of an automobile, and particularly to the type having horizontally disposed vertically spaced rails.

One object of the invention, is to provide a readily attachable and detachable strap support (carrying a flexible buckle strap) adapted to interlockingly engage with said rails, in a manner whereby the strap support is caused to frictionally grip one of the rails by the pull of the strap, when the latter is strapped around a bundle.

A further object of the invention, is to provide a device of the class described, which will be neat in appearance, simple, useful and cheap of manufacture, and which may be left positioned on the luggage carrier, when not in use, it having means whereby it may be firmly bound to the rails to prevent rattling.

To this end one form of the invention consists in the construction, combination and arrangement of parts hereinafter described and claimed.

In the accompanying drawings forming part of this specification:

Figure 1 is a perspective view of my invention, showing it applied to the rails of a luggage carrier designed to be folded to lie flat upon the running board.

Figure 2 is an enlarged front view of the invention.

Figure 3 is a side view of same.

Figure 4 is a side view of the invention illustrating the manner of detaching it from the rails, and

Figure 5 is a modified form of the clamping end of the strap support.

A designates the running board of an automobile. B represents one of a plurality of uprights of a luggage carrier, each upright having a hinge connection b, with a clamp portion c, whereby the upright may be folded against the top of the running board, as indicated in dotted lines (Fig. 1).

D and D' represent respectively, the top and bottom rails of the luggage carrier, and

are shown formed of thin flat straight bars of parallel width.

My invention comprises a long thin supporting plate E positioned vertically at 60 right angles to the rails D and D', and extending beyond the respective upper and lower edges 1 and 2 of said rails.

Below the rail D', the plate E has two adjacently positioned horizontal parallel 65 slots 3 and 4, one above the other, said slots being in vertical alignment with an outwardly and upwardly inclined lug 5, extending from the outer face 6 of the plate.

Positioned in a horizontal plane, symmetrically with respect to and above said lug, are the outwardly extending stop lugs 7, spaced from the base of said lug so as to receive the rail D' widthwise between them. Thus, when the plate is held positioned at an angle, as shown in Figure 4, the rail may be brought to rest in the crotch formed be-

tween the lug and plate, and the plate then be swung toward and against the rail D, to the position shown in Figure 3, thereby locking the plate against vertical movement, and by means of the stop lugs, against movement in the plane of the rails. At the top, the plate is formed with a rectangular aperture 8, the sides thereof parallel with the 75 long edges of the plate.

Spaced a distance below the aperture, and outwardly from the outer face of the plate, is the eye 9, revolvably supporting the cross member 10, of a U shaped hook F, the legs 12 of the U being 90 bent outwardly to form a pair of hooks 11. The legs are projectable through the rectangular chain link 13, and are adapted to hook over the outer side 14 thereof. The link enters loosely widthwise into the aperture 8, and projects therethrough, so that the ordinary flat buckle strap 15 having buckle 16, may be strung through link as shown in Figures 1 and 2.

Referring now to Figure 4, it will be 100 noted, that the aperture 8 is sufficiently wide to permit a loop formed by doubling the strap upon itself to be projected through it, the loop carrying the link 13. When the plate is swung against the rail D, the latter 105 will loosely fit between the eye 9 and the aperture 8. The hook F is now swung over the outer face of the rail, and the eye inserted into the hooks 11. Obviously, when the strap, (which is strung through the slots 110 3 and 4) is drawn taut, the legs of the hook F will press the rail against the face of the

plate, A (Fig. 3) the degree of pressure exerted depending upon the stress of the strap. As the strap lies flatly against the inner surface of the plate, the pull on the link 13, 5 and the bar 3' formed by the plate between the slots 3 and 4, is in a general transverse direction relative to the plate. A bundle embraced by the strap and plate will be pressed against the latter and held firmly, the 10 straight plate preventing any unsightly bulging outwardly of the luggage between the rails such as blankets and the like. Any number of the devices may be used, one only being shown in the drawings. When not in 15 use, the plate alone may be strapped to the rail so as to prevent rattling. As the plate is thin, and the back thereof free from projections, it will lie flatly upon the running board when the luggage carrier is in folded 20 position. In Figure 5 is shown a modified form, wherein the hook F and the link 13 are combined in a single member.

The hook F may be termed a lever, and with the link 13, a swingable element extending from one side of the plate to the other.

I claim:

1. A device of the class described, comprising a long plate, means at one end of the plate for holding a flexible strap so that it 30 may be brought to lie flatly longitudinally on one side of the plate, means adjacent said holding means for interlockingly engaging a transverse rail, and a hinged lever formed with a detachable strap holding member located a distance from the other end of said plate on the other side thereof and swingable toward said strap and loosely slidably engageable by means of said detachable member with said strap, the hinge of said 40 lever being spaced from the flat surface of said plate.

2. The combination with rails positioned in spaced relation one above the other, a plate extending transversely across the rails 45 and positioned against them, means at the lower portion of the plate for holding longitudinally slidably a flexible strap, a readily detachable pivotal connection between the lower rail and the plate, an aperture in the 50 top portion of the plate to loosely receive the loop of a strap formed by folding same upon itself, a bendable rail engaging element hinged to the plate so as to swing against the upper rail, and formed with a strap 55 receiving part capable of being bent over the top of the rail, to receive a flexible strap so as to be longitudinally slidable therein and adapted to extend through said aperture.

3. In a device of the class described, the combination with parallel rails in spaced relation, and a flexible tie member adapted to surround a bundle and to be held in taut position thereon, of a plate extending transversely across said rails and resting thereagainst and having at one end means for supporting said tie member so as to be longitudinally slidable thereon and having at 60 said end a connection with one of said rails, an opening at the other end of said plate, and a rail engaging element including a link at 65 its outer extremity pivoted on said plate to swing against the other of said rails and thereby project said link through said opening to slidably receive said tie member.

4. In a device of the class described, in combination with parallel spaced rails and a flexible strap capable of being drawn taut around a bundle and so held, of a long plate extending transversely across said rails and resting thereagainst and swingingly supported at one end on one of said rails, and flatly positioned lengthwise against said strap, means at one end of the plate for holding said strap, an aperture at the other end of said plate, and means, including a 85 bendable lever hinged to said plate extending around the other of said rails and through said aperture and around said strap, whereby when said strap is drawn taut the stress thereof will actuate said lever 90 to press said last named rail against said plate.

5. The combination with horizontally disposed rails of the class described, spaced one above the other, of a flat plate extending 95 from a position below the lower rail to a position above the upper rail, an aperture in said plate above the upper rail, a chain link member projectable through said aperture and of a length to extend beyond the opposite flat surfaces of said plate, means for holding a strap longitudinally slidable at the bottom of said plate, a packing strap projected through the extending portion of said link on one side of said plate and extending 100 to and engaging with said means to be longitudinally slidably held thereby, and a hook 105 swingingly supported on said plate at a position below the top rail and swingable upwardly over said rail and extending beyond the top thereof and engaging with the extending portion of said link on the other side of said plate.

In testimony whereof I affix my signature,

JULIUS M. BORN.
